UNITED STATES PATENT OFFICE.

ALLAN JAY WAY, OF WELLINGTON, NEW ZEALAND.

CARBURETER.

No. 857,180.

Specification of Letters Patent.

Patented June 18, 1907.

Application filed February 14, 1906. Serial No. 301,030.

To all whom it may concern:

Be it known that I, ALLAN JAY WAY, a British subject, and a resident of 55 Lambton Quay, Wellington, in the Colony of New Zealand, have invented certain new and useful Improvements in Carbureters, of which the following is a specification.

My invention relates to that class of apparatus for carbureting air and producing a combustible gas for lighting and heating purposes, in which hot air is sent under pressure through a carbureter, where it is mixed with hydrocarbon vapor, and passing out is mixed with a further quantity of hot air before passing to the burners for consumption.

The object of my invention is to provide more efficient means for heating the hydrocarbon (say petrol) lying in the carbureter, and more efficient means for effecting the vaporization of the petrol and its mixture with the hot air admitted to the carbureter.

My invention consists in an improved construction of carbureter and heating apparatus and a special form of hot-air injector therefor, as hereinafter described, and particularly pointed out in the claims.

Referring to the accompanying drawings, in which similar numerals of reference indicate similar parts, Figure 1 is a part sectional side view of a suitable form of apparatus with my improvements applied thereto. Fig. 2 is an end view of the carbureter with parts broken away to show some of the interior arrangements. Fig. 3 is an enlarged longitudinal sectional view of my special form of injector. Fig. 4 is an end view of the injector.

The general arrangement of the apparatus shown in Fig. 1 is as follows:—There is a framework (1) supporting a bellows (2) or other suitable device for drawing air from the atmosphere and driving it under pressure through the pipe (26) to the air-heater (3) which may be of any known suitable type. The bellows is operated by the shaft (4) driven by an engine or motor (not shown) of any suitable type. From the air-heater (3) the hot air passes through the pipe (5), portion being admitted to the carbureter (7) as hereinafter described, through the short pipe (6) provided with the regulating cock (10). The carbureter (7) is supported on the framework (1) and carries the petrol reservoir (8) which is in constant communication with the carbureter (7) by means of the pipes (9), there being therefore a constant supply of liquid petrol (15) covering the bottom of the

carbureting chamber. An outlet pipe (11) with cock (12) leads the carbureted air or gas into the main (13) where it is mixed with a further quantity of hot air coming from the pipe (5) provided with cock (14), the mixture then passing to the burners for consumption.

Referring now to my improvements:—The carbureter (7) has a liquid-proof false bottom (16) to the carbureting-chamber, on which lies the liquid petrol (15) and below the false bottom is a hot-water-chamber (17) which is continued at one end so as to extend beyond and a little up the side of the carbureting-chamber, leaving an open portion (18) by means of which the water may be poured in and its temperature readily ascertained. A gas or other burner (19) of suitable construction is mounted below the hot-water-chamber (17) for the purpose of heating the water contained therein, thus generating heat which acts on the petrol lying on the false bottom (16) of the carbureting-chamber, and raises it to the desired temperature. Within the carbureting-chamber transverse perforated baffle plates (20) (21) (22) are provided, which are placed preferably as shown in Figs. 1 and 2. These baffle plates may be made of metal gauze, or perforated zinc or other metal, and are for the purpose of breaking up and completing the vaporization of the petrol which together with hot air is projected upon the baffle plates by the injector (23) as herein-after described. The baffle plates also complete the mixture of the hot air with the petrol. The injector (23) is of special form, and is illustrated more particularly in Figs. 3 and 4. It is mounted in the wall of the carbureting-chamber, and connects with the pipe (6) bringing the hot air under pressure from the pipe (5). The injector has a tapered nozzle (24) which has preferably integral therewith and near its outlet a backwardly extending pipe (25) which I term the suction pipe. The injector is arranged so that the lower end of its suction pipe (25) is normally immersed in the liquid petrol (15) lying on the false bottom (16) of the carbureting-chamber.

The operation of the apparatus shown is as follows:—The water in the hot-water-chamber (17) is kept heated by means of the burner (19) so as to raise to the desired point the temperature of the liquid petrol (15) lying on the false bottom (16) of the carburet-

ing-chamber. The bellows (2) is set in motion, supplying air under pressure through the pipe (26) to the air-heater (3) where it is heated, the hot air passing up the pipe (5) and portion being drawn off by the short pipe (6). The cock (10) being opened to the desired extent, hot air rushes into the injector (23), the tapered nozzle of which increases the pressure as the hot air passes onward, the passage of the hot air causing petrol to be drawn up from the bottom (16) of the carbureting-chamber through the suction pipe (25) into the nozzle (24) this petrol mingling in the mouth of the nozzle with the hot air and discharging therewith against the baffle plates (20) (21) (22) which break it up and complete the vaporization of the petrol and its mixture with hot air. The carbureted air or gas is led off by the pipe (11) and, the cocks (12) and (14) having been opened, it passes on to the burners for consumption, receiving on the way an additional mixture of hot air from the pipe (5).

While I have shown my improvements applied to one particular form of apparatus,

I do not confine myself to their use with only such an apparatus, as they may be applied to any suitable apparatus of the class described.

Having now described my invention, what I claim as new and desire to secure by Letters Patent is,—

A carbureter comprising a carbureting chamber, vertical perforated partitions therein extending from the top and bottom, means for feeding liquid petrol to said chamber, means for heating the chamber and a tapered nozzle for introducing air to said chamber, said nozzle having a branch extending rearwardly and downwardly from adjacent the outlet end thereof, the lower end of said branch being immersed in the petrol.

In testimony whereof I have signed my name to this specification in the presence of two subscribing witnesses.

ALLAN JAY WAY.
